FUEL INJECTION ARRANGEMENTS IN
INTERNAL-COMBUSTION ENGINES

Ove Petersen, Gentofte, Denmark

Application January 25, 1946, Serial No. 643,282
In Denmark February 4, 1943Section 1, Public Law 690, August 8, 1946
Patent expires February 4, 1963

5 Claims. (Cl. 123—139)

1

Fuel injection arrangements are known for internal combustion engines with two fuel pumps working in series. The first, so-called normal, fuel pump is driven by the engine, and the pressure pipe of the pump opens out through a spring-loaded suction valve in the pressure chamber of the second fuel pump, the so-called pressure pump, which has a differential piston and works in accordance with the principle disclosed in British Patents Nos. 226,523 and 419,510, the piston being driven by the compression- and combustion-pressures in the cylinder. From the pressure chamber of this second fuel pump a pressure channel leads to an automatic, spring-loaded fuel valve in the cylinder of the engine. From the said pressure channel a relief channel is branched off, which ends either in the suction pipe of the pressure pump or in a closed liquid chamber of the necessary volume. In the relief channel is inserted a control member—preferably a slide valve formed by the piston of the pressure pump—which opens when the fuel valve in the cylinder is to close. The arrangement has the drawback that it requires two pumps working in series, of which the first measures out the quantity of oil to be injected into the cylinder by the second pump, the pressure pump. Furthermore there is the essential drawback that the moment of opening of the fuel valve will depend in part on the spring pressure on the automatic valve, in part on the pressure on the oil, which pressure is in turn determined by the compression in the engine cylinder. The arrangement cannot therefore offer any exact determination of the moment of the commencement of the fuel injection into the cylinder.

Furthermore another fuel injection arrangement is known with two pumps working in series. The first and normal fuel pump measures out the quantity of fuel which the other pump is to inject into the cylinder. The fuel is delivered from the first pump to an accumulation chamber which is provided with a spring-actuated accumulator piston which controls an overflow channel. From the accumulation chamber the fuel is pressed through a non-return valve into the pumping chamber for the second pump, the so-called pressure pump, which has a differential piston which during the pressure stroke is driven in part by a spring, in part by the compression- and combustion-pressure in the cylinder. From the pressure chamber of the pressure pump the fuel flows off through a valve to a pressure pipe which terminates in a spring-actuated automatic fuel injection valve in the cylinder. In the said

2

pressure pipe a control member is inserted. This control member consists of a slide valve which is spring-influenced in such a way that—unless the spring pressure is overcome—it will close the pressure pipe. The said slide valve is actuated for opening by means of a lever that is rotatable around a shaft, the other end of which lever is actuated indirectly from a so-called negative cam on a cam disc on a control shaft. The said slide valve control is so arranged that the slide valve will open the pressure channel to the automatic fuel valve at the moment when the fuel injection into the cylinder is to commence. The construction thus constituted gives a good determination of the point of commencement of the injection but gives no good determination of the termination of the injection, the construction lacking means for the elimination of the pressure in the valve at the termination of the injection. Moreover, the construction has besides the drawback that there is no relief channel communicating with the pressure pipe of the fuel pump, the drawback that the construction requires two series-operated pumps, namely, besides the gas-driven pump furthermore a normal fuel pump which measures out the quantity of fuel to be injected and which through a non-return valve presses the fuel into the pressure chamber of the gas-driven pump and thereby causes the differential piston of this pump to be returned into its original position under overcoming of especially the spring-pressure which constantly influences the piston in the gas-driven pump.

Furthermore a fuel injection arrangement is known consisting of a combined fuel pump and injection valve, the rotating differential piston of which is, during the pressure stroke, driven by the compression- and combustion-pressure in the cylinder and is, during the suction stroke, driven by a spring. From a tank the fuel is led to a bore in the case of the pump, and from this it is sucked through an oil inlet into the pressure chamber of the pump. During the pressure stroke the pump piston closes the oil inlet and brings the fuel under increasing pressure in the pumping chamber. From the pumping chamber a pressure channel issues, the first part of which forms a channel in the pump case and the last part of which consists of a bore in the pump piston. This bore terminates in a lower space in the piston, which space is below bounded by a wall in which there are a number of nozzle openings leading into the cylinder. In the lower part of said space a spring-loaded non-return valve is

provided which is opened when the pressure on the fuel overcomes the spring pressure of the valve. Next the fuel will start its injection into the cylinder through said nozzle openings. In the said channel in the pump case, that is in the former part of the pressure channel of the pump, there is a spring-influenced valve, the so-called timing valve. In this a relief channel is formed which can put the pressure channel of the pump in communication with the suction chamber of the pump or the said bore in the pump case. The said relief channel in the timing valve can be closed by means of another valve. This other valve can close the relief channel, as with its head it can be brought to abut on the end of the timing valve which projects into the suction chamber of the pump. The said other valve is by means of a tappet actuated indirectly from a cam disc on a control shaft. A positive cam on the cam disc causes the said other valve to first close the relief channel in the timing valve and then a little later open the latter, whereby the pressure channel from the pumping chamber of the pump is opened. When the timing valve is opened the fuel injection into the cylinder will start, and during the pressure stroke of the pump piston the fuel injection will occur at an increasing pressure. The injection period will continue until the mechanically actuated timing valve is closed on account of the cam control and the spring influence. Shortly after the timing valve has been closed, the cam control will permit the other valve to open the relief channel. The construction has the very considerable drawback that the point of commencement for the injection in fact becomes indeterminate, it being necessary to work up a pressure in the last part of the pressure channel and in the space containing the non-return valve, before the latter can start opening. The passage of the fuel through the non-return valve and thereby also the fuel injection through the nozzle openings will consequently start at a rather slowly increasing pressure, so that the point of commencement for the injection becomes indeterminate. The termination of the injection is in fact also quite indeterminate, said termination being first and foremost determined by the closing of the timing valve a short time before the relief channel is opened, which will cause the pressure on the fuel in the pressure channel and the lower chamber of the latter to drop until the non-return valve starts and performs its closing motion, all with the result that the termination of the injection is in fact quite indeterminate. Furthermore there is the drawback that the relief channel terminates in the suction chamber of the pump, which can give rise to shocks in the pump.

Finally another fuel injection arrangement is known likewise consisting of a combined fuel pump and injection valve. The suction stroke of the pump piston is caused by a spring, and the pump works in accordance with the said British Patents Nos. 226,523 and 419,510, the stepped piston being during the pressure stroke driven by the compression- and combustion-pressure in the cylinder of the engine. On the pump piston there are a couple of oblique cutting-off edges, which serve for measuring a certain quantity of oil in the pressure chamber of the pump. From this leads a pressure pipe to the injection channel of the valve, which channel ends freely in the cylinder. In the pressure pipe, which is in part made up of the nearly tubular pump piston, is inserted a control member in the form

of a slide valve, which through a spring-actuated control spindle projecting up through the combined pump and valve is driven from a cam shaft. The construction is also known in some modified embodiments, but common to all embodiments is the fact that the pressure channel terminates in an open nozzle, and that in the lowest part of the pressure channel there is a control member in the form of a slide valve or a so-called timing piston valve which on one hand is to determine the commencement of the injection in the best possible way, and on the other hand—when the injection is about to cause—acts to such the last remainder of the fuel back into the pressure channel so that the open nozzle is prevented from dribbling. The construction described is very complicated, and as a result of the pressure channel forming a channel open at the end it has the drawback that the moment for the commencement and the initial pressure of the injection are not precisely defined, the opening for the pressure channel by the slide valve causing a pressure drop in the pumping chamber, so that the injection is started at a comparatively low pressure, which is inexpedient for the combustion. The injection is terminated when the pump piston arrives at its innermost position after which the pressure in the pressure channel will drop as the oil in the channel will expand. This relatively slow termination of the injection is a considerable drawback.

The purpose of the present invention is to remedy the said drawbacks by an injection arrangement mainly of the kind mentioned above and thereby ensure an accurate determination of the moment of commencement of the fuel injection as well as the termination of the latter.

More clearly defined the invention relates to a fuel injection arrangement for internal combustion engines of the kind where the piston of the fuel pump is a stepped piston driven by the compression- and combustion-pressure of the engine, and where the suction stroke of the piston is caused by a spring, and in which fuel pump a helical cutting-off edge, preferably situated on the piston, serves for measuring the quantity of oil intended for injection, and in the pressure channel of which is inserted a control member, preferably a slide valve. The feature that is first and foremost characteristic of the invention is that outside the control member, which is preferably formed by a slide valve, the pressure channel of the pump is connected to one or more automatic, spring-loaded fuel valves in the cylinder, and that from the pressure channel of the pump there leads a relief channel leading to a return pipe to the oil tank of the pump, in which channel there is in a way known per se inserted a control member, which is preferably made up of a slide valve formed by the lower part of the pump piston.

By the said fuel injection arrangement a precise determination of the moment of commencement of the injection is ensured by the control member, preferably a slide valve, which is inserted between the pump and the spring-loaded fuel valve in the cylinder, the stepped piston of the pump being so proportioned that the oil pressure before the said control member or slide valve is so high at the moment, when the control member is opened, that the fuel valve is opened at practically speaking the same moment, i. e. at the first pressure wave. At the same time there is by a suitable adjustment

of the spring loading of the fuel valve attained that the injection through the valve may be started at the injection pressure most favourable for the combustion. The arrangement also ensures a precise determination of the termination of the fuel injection, the quick relief of the pressure in the fuel valve attained by the pressure pipe being at the end of the injection put in communication with the said return pipe causing a quick closing of the fuel valve, so that the injection is likewise terminated at a pressure favourable for the combustion, while at the same time by the use of the said return pipe disturbing pressure variations in the supply pipe for the fuel pump are avoided.

The piston of the fuel pump is in accordance with the invention advantageously shaped so at the top that in part it has a cutting-off edge known per se for cutting off the oil exit to the pressure channel, in part has one or more, preferably helical, cutting-off edges known per se for cutting off at least one oil inlet to the pressure chamber of the pump.

On the accompanying drawing is shown an embodiment of a fuel injection arrangement in accordance with the invention, the figure showing a vertical central section through the pump and the pressure channel of the latter with appurtenant control member.

1 is the case of the pump and 2 a liner in the latter. The pump piston 3 is below connected with another piston 4 which can move in a cylinder 5, in the bottom of which there is a channel 6. As the pump works in accordance with the Archauloff system, the channel 6 is in communication with the compression space in a motor engine cylinder, so that the pressure from the latter is introduced under the piston 4. 7 is a spring serving for pulling the pistons 3 and 4 downwards through a traverse arrangement, which has only been indicated by dotted lines on the drawing.

In the case 1 or liner 2 of the pump or in both parts there are shaped various channels in communication with the pressure chamber 8 of the fuel pump. 9 is an oil supply channel supplying the oil preferably from a preliminary supply pump, when the piston 3 is in the lowest position shown on the figure. From the channel 9 lead one or more oil entries 10 to the pressure chamber 8. Somewhat higher in the pressure chamber is an oil exit 11 to a pressure channel 12, but instead of a single exit 11 there may be several such exits. Outside the case 1 the pressure channel 12 passes through a slide valve case 13, and on the other side of the latter it communicates with one or more fuel injection valves, which are not shown on the drawing, but which are normal automatic and spring-loaded valves. From the pressure channel 12 leads a relief channel 14 communicating with a return pipe to the oil tank of the pump, for which relief channel the piston 3 forms a slide valve, the channel 14 being in a part interrupted by the piston, which at a distance from the top has a clearance 15 which can be made to correspond with the said part of the relief channel.

The pump piston 3 controls the oil entries 10 and the oil exit 11 to the pressure channel 12 and contingently the inlet to the relief channel 14, if the latter leads from the pressure chamber 8. At the top the piston has an edge 16 for cutting off the oil exit 11 to the pressure channel 12. The top of the piston has furthermore been shaped so that preferably in connec-

tion with the edge 16 there are one or more preferably helical cutting-off edges 17 for cutting off the oil entry 10 shown to the right in the figure, which entry is the last to be closed during the upward movement of the piston. The piston 3 can be turned, and the degree of filling of the pump thereby be regulated, the edge 17 sooner or later cutting off the oil entry 10 closed last.

The distance between the cutting-off edge 16 of the pump piston for the oil exit 11 and the upper edge of the clearance 15 in the pump piston is, as the figure shows, equal to the distance between the upper edge of the oil exit 11 and the upper edge of the entry and exit in the liner 2 or the case 1 of the relief channel 14.

In the slide valve casing 13 the pressure channel 12 is controlled by a slide valve 18 with a clearance 19. The slide valve is connected with 20 a roller holder 20 having a roller 21. A spring 22 or a corresponding member presses the slide valve downwards and thereby the roller 21 against a cam disc 23, the cam 24 of which is a so-called negative cam. The cam disc 23 is fitted on a control shaft 25, the aim of which is solely to move the slide valve 18, on which there is practically no load, and therefore the control shaft may be very slender. The control shaft may in a way known per se be intended for, by turning or shifting, reversing the slide valve motion corresponding to ahead and astern working respectively. This reversing may be effected by a handle on the starting platform, there being normally required no great work for that.

The arrangement shown and described works in the following way.

The pressure in the cylinder is transferred through the channel 6 and will move the piston 3 upwards, so that the cut-off edge 17 will close the oil entry 10 to the right in the drawing. The fuel oil measured out will thereby be confined in the pressure chamber 8 and in the pressure channel 12, which is closed by the slide valve 18. The pressure on this quantity of oil increases while the compression in the cylinder increases. The cam 24 on the control shaft 25 is adjusted so that the slide valve 18 will open the pressure channel 12 at the exact point when the fuel oil injection through the valve or valves is to be commenced, or rather so much earlier as required by the dead work of the system. The slide valve 18 thus determines the moment of opening for the spring-loaded fuel valve or valves. The gas pressure will continue moving the piston upwards and press the oil in through the valve or valves. When the piston 3 has moved so much upwards that it cuts off the oil exit 11 to the pressure channel 12, the piston is checked by the quantity of oil confined over the piston in the pump case. Coincident with the cutting-off edge 16 concluding the cutting-off of the oil exit 11 to the pressure channel the clearance 15 in the piston 3 will begin to open the relief channel 14, so that the pressure channel 12 is put in communication with the relief channel 14, which leads to a return pipe to the oil tank of the pump. Consequently the pressure in the pressure channel 12 and the valve will be relieved, whereby a sudden closing of the fuel valve or valves is ensured.

As a result of the fact that the distance between the cutting-off edge 16 and the upper edge of the clearance 15 in the pump piston 3 is equal to the distance between the upper edge of the oil exit 11 and the upper edge of the exit and

entry in the liner 2 of the relief channel 14 the moment for covering the oil exit 11 in relation to the moment of opening the relief channel 14 will coincide that is to say the relief channel 14 will just have been fully opened when the cutting-off edge 16 has just completed the closing of the oil exit 11 to the pressure channel 12, so that the relief of the pressure in the pressure pipe 12 occurs quickly enough for ensuring a good closing of the fuel valve or valves, while at the same time the travel of the piston 3 will not get too large during the time, in which the relief of the pressure takes place. By this means a protection against shocks in the pump is attained.

The spring 22 or the corresponding arrangement, e. g. a weight load, which keeps the roller 21 on the slide valve 18 against the cam 24 on the control shaft ensures that—if from one cause or another the slide valve should get stuck in the slide valve casing 13—the slide valve 18 will always get stuck in its highest position, so that the oil supply to the valve or valves will be cut off. If the slide valve 18 gets stuck the oil will simply be confined in the pump case, and the ignition in the particular cylinder will then cease, so that the fault will at once be detected and may be remedied. The construction of the control of the slide valve 18 makes it impossible that any considerable irregularities in the working may arise out of a slide valve getting stuck entailing too high ignitions or the like.

As the slide valve 18 may be fitted at any place in the pressure channel 12 the position of the control shaft 25 may be chosen with due regard to the expediency of the construction and the accessibility of the shaft.

By adjustment of the cam 24 on the control shaft an exact determination of the moment of opening of the valve, i. e. of the moment of ignition may be ensured.

The invention is not limited to the pump arrangement shown and described, as it is not necessary that the control members for the pressure channel 12 and the relief channel 14 are shaped as slide valves, as these control members or only one of them may consist of a valve or another suitable control member. In the embodiment shown the pump piston 3 forms a slide valve for the relief channel 14, but this may be controlled by another slide valve than the piston 3, contingently by the slide valve 18 which controls the pressure channel 12. The measuring of the quantity of oil intended for injection may in the pump be effected in other ways than by a cutting-off edge 17, preferably helical, situated on the piston, as there may be an independent control member for the particular oil inlet.

I claim:

1. A fuel injection arrangement for internal combustion engines comprising a fuel pump including a cylinder having a pressure chamber therein and a pump piston mounted for reciprocation in the pump cylinder, said pump piston including a large stepped portion, a spring for effecting the suction stroke of the pump piston, a second cylinder, a pipe forming communication between the combustion space of the engine and the second cylinder in which the stepped portion of the pump piston is mounted for reciprocation so that during the pressure stroke the stepped pump piston is driven by the compression- and combustion-pressure of the engine, at least one fuel inlet to the pressure chamber, at least one cutting-off edge situated in the pump and dis-

posed obliquely in relation to the axis of the pump piston, which cutting-off edge in cooperation with said fuel inlet acts for measuring off in the pump the volume of oil intended for being injected into the engine cylinder, a fuel outlet from the pressure chamber, a pressure channel leading from the fuel outlet, at least one automatic, spring-loaded fuel valve in the engine cylinder and communicating with the pressure channel, a control member inserted in the said pressure channel between the fuel pump and said valve for the timed opening of said pressure channel, a relief channel leading from said pressure channel at a point between said control member and the fuel outlet to a return pipe to the oil tank of the pump, and a control member situated in said relief channel for the timed opening of the relief channel.

2. A fuel injection arrangement as claimed in claim 1 wherein the first control member is constituted by a slide valve provided with a clearance and a roller and said slide valve is operated by a negative cam on a control shaft, the roller being spring pressed against said cam.

3. A fuel injection arrangement as claimed in claim 1 wherein the second control member is constituted by a clearance formed in the pump piston, said relief channel communicating with the pump cylinder and fluid passage therethrough being controlled by said clearance, said relief channel at the point of communication with the pump cylinder having, in the direction of the axis of the pump piston, the same extent as the clearance.

4. A fuel injection arrangement for internal combustion engines comprising a fuel pump including a cylinder having a pressure chamber therein and a pump piston mounted for reciprocation in the pump cylinder, said pump piston including a large stepped portion, a spring for effecting the suction stroke of the pump piston, a second cylinder, a pipe forming communication between the combustion space of the engine and the second cylinder in which the stepped portion of the pump piston is mounted for reciprocation so that during the pressure stroke the stepped pump piston is driven by the compression and combustion pressure of the engine, at least one fuel inlet to the pressure chamber, said pump piston having a first cutting-off edge thereon disposed obliquely to its axis, which cutting off edge in cooperation with said fuel inlet acts for measuring off in the pump the volume of oil intended for being injected into the engine cylinder, a fuel outlet from the pressure chamber, said pump piston having a second cutting-off edge formed at its top and disposed in a plane at right angles to its axis, said second cutting-off edge cooperating with said fuel outlet, a pressure channel leading from the fuel outlet, at least one automatic, spring-loaded fuel valve in the engine cylinder and communicating with the pressure channel, a first control member interposed in the said pressure channel between the fuel pump and said spring-loaded fuel valve for the timed opening of said pressure channel, a relief channel leading from said pressure channel at a point between said control member and the fuel outlet to a return pipe to the oil tank of the pump, and a second control member formed on said piston and interposed in said relief channel for the timed opening of the latter.

5. A fuel injection arrangement as claimed in claim 4 wherein the second control member is constituted by a clearance formed in the pump

piston, said relief channel communicating with the pump cylinder and fluid passage therethrough being controlled by said clearance, said relief channel at the point of communication with the pump cylinder having, in the direction of the axis of the pump piston, the same extent as the clearance, the pump piston being rotatable for varying the volume of fuel for injection into the engine cylinder, and the distance between the second cutting-off edge and the clearance in the pump piston being the same as the distance between the edge of the fuel outlet situated nearest the inner end of the pressure chamber in the pump and the edge at the point of communication between the relief channel and the pump cylinder situated nearest said end of the pressure chamber.
